[57] ABSTRACT

Compounds of the formula

wherein

R_1 represents alkyl having 1 to 4 carbon atoms, alkenyl having 3 to 5 carbon atoms, or alkynyl having 3 to 6 carbon atoms,

R_2 represents hydrogen, alkyl having 1 to 4 carbon atoms, alkenyl having 3 to 5 carbon atoms, or alkynyl having 3 to 6 carbon atoms,

R_3 represents alkyl having 1 to 4 carbon atoms,

R_4 represents alkyl having 1 to 4 carbon atoms, and

R_5 represents hydrogen, or alkyl having 1 to 4 carbon atoms, and

X represents an inorganic or organic acid radical and their acid addition salts, process for the manufacture of these compounds, compositions containing these compounds as active ingredients and use of these compounds for the control of parasitic pests on domestic and productive animals.

2 Claims, No Drawings

PHENYLFORMAMIDINE DERIVATIVES

The present invention relates to phenylformamidines, to processes for their production, and to their use in pest control.

The phenylformamidines correspond to the formula

- a) SOC_1I_2
- b) COC_1I_2
- c) POC_1I_3
- d) PC_1I_3
- e) PC_1I_5
- f) $(\text{CH}_3)_2\text{SO}_4$
- g) $\text{C}_1\text{I}_3\text{O}_2\text{S}_2\text{O}_4$

or to the formula

wherein

R₁ represents alkyl having 1 to 4 carbon atoms, alkenyl having 3 to 5 carbon atoms, or alkynyl having 3 to 6 carbon atoms,

R₂ represents hydrogen, alkyl having 1 to 4 carbon atoms, alkenyl having 3 to 5 carbon atoms, or alkynyl having 3 to 6 carbon atoms,

R₃ represents alkyl having 1 to 4 carbon atoms,

R₄ represents alkyl having 1 to 4 carbon atoms, and

R₅ represents hydrogen, or alkyl having 1 to 4 carbon atoms, and

X represents an inorganic or organic acid radical.

The alkyl, alkenyl, alkynyl or alkoxy groups applicable for formula I can be straight-chain or branched, interrupted with hetero atoms, unsubstituted, or substituted, e.g. with halogen. Halogen is fluorine, chlorine, bromine and/or iodine.

Examples of such groups are inter alia: methyl, methoxy, trifluoromethyl, ethyl, ethoxy, 2-chloroethyl, propyl, propoxy, isopropyl, isopropoxy, n-butyl, n-butoxy, i-, sec.- or tert.-butyl, allyl, methallyl, 1-chloroallyl, 2-chloroallyl, 1-butenyl, 2-butenyl, 3-butenyl, propargyl or isobutynyl.

Compounds of formula I and Ia preferred because of their action are such compounds wherein

R₁ represents methyl, ethyl, propyl, isopropyl, or n-butyl,

R₂ represents hydrogen, methyl, ethyl, propyl, isopropyl or n-butyl,

R₃ represents methyl, ethyl or isopropyl,

R₄ represents methyl, ethyl, propyl, isopropyl, sec.-butyl or tert.-butyl, and

X represents an inorganic or organic acid radical.

10

The compounds of formula I and Ia can be produced by methods known per se; for example, by the following method:

30 In formulae II and III, the symbols R₁ to R₄ have the meanings given for formula I. The starting materials of formulae II and III are known, and can be produced by methods analogous to known methods.

The compounds of formula I have a broad biocidal action, and can be used for the control of parasitic pests on domestic and productive animals. The compounds of formula I possess, in particular, acaricidal properties.

35 Surprisingly, the compounds according to the invention are appreciably more stable than analogous compounds disclosed in the literature, and have therefore a clearly more persistent action against all development stages, such as eggs, larvae and adults of members of the order acarina, particularly of mites, red spider mites and ticks, such as, e.g. of the families Ixodidae, Argasidae, Tetranychidae and Dermanyssidae.

40 The acaricidal action of the said compounds can be substantially broadened and adapted to suit the given circumstances by the addition of other biocidal compounds. Suitable additives include the following active substances:

50 ORGANIC PHOSPHORUS COMPOUNDS

Bis-0,0-diethylphosphoric acid anhydride (TEPP)

Dimethyl-(2,2,2-trichloro-1-hydroxyethyl)-phosphonate (TRICHLORFON)

55 1,2-dibromo-2,2-dichloroethyldimethylphosphate (NALED)

2,2-dichlorovinylidimethylphosphate (DICHLOVOS)

2-methoxycarbamyl-1-methylvinylidimethylphosphate (MEVINPHOS)

60 Dimethyl-1-methyl-2-(methylcarbamoyl)-vinylphosphate cis (MONOCROTOPHOS)

3-(dimethoxyphosphinyl)-N,N-dimethyl-cis-crotonamide (DICROTOPHOS)

2-chloro-2-diethylcarbamoyl-1-methylvinylidimethylphosphate (PHOSPHAMIDON)

0,0-diethyl-0(or S)-2-(ethylthio)-ethylthiophosphate (DEMETON)

S-ethylthiocetyl-0,0-dimethyl-dithiophosphate (THIOMETON)

0,0-diethyl-S-ethylmercaptopmethyldithiophosphate (PHORATE)
 0,0-diethyl-S-2-(ethylthio)ethyldithiophosphate (DISULFOTON)
 0,0-dimethyl-S-2-(ethylsulphinyl)ethylthiophosphate (OXYDEMETON METHYL)
 0,0-dimethyl-S-(1,2-dicarbethoxyethyl)dithiophosphate (MALATHION)
 0,0,0,0-tetraethyl-S,S'-methylene-bis-dithiophosphate (ETHION)
 0-ethyl-S,S-dipropylidithiophosphate
 0,0-dimethyl-S-(N-methyl-N-formylcarbamoylmethyl)-dithiophosphate (FORMOTHION)
 0,0-dimethyl-S-(N-methylcarbamoylmethyl)dithiophosphate (DIMETHOATE)
 0,0-dimethyl-0-p-nitrophenylthiophosphate (PARATHION-METHYL)
 0,0-diethyl-0-p-nitrophenylthiophosphate (PARATHION)
 0-ethyl-0-p-nitrophenylphenylthiophosphate (EPN)
 0,0-dimethyl-0-(4-nitro-m-tolyl)thiophosphate (FENTHION)
 0,0-dimethyl-0-2,4,5-trichlorophenylthiophosphate (RONNEL)
 0-ethyl-0,2,4,5-trichlorophenylethylthiophosphate (TRICHLORONATE)
 0,0-dimethyl-0-2,5-dichloro-4-bromophenylthiophosphate (BROMOPHOS)
 0,0-dimethyl-0-(2,5-dichloro-4-iodophenyl)-thiophosphate (JODOFENPHOS)
 4-tert.butyl-2-chlorophenyl-N-methyl-0-methylamido-phosphate (CRUFOMATE)
 0,0-dimethyl-0-(3-methyl-4-methylmercaptophenyl)-thiophosphate (FENTHION)
 Isopropylamino-0-ethyl-0-(4-methylmercapto-3-methylphenyl)phosphate
 0,0-diethyl-0-p-(methylsulphinyl)phenyl-thiophosphate (FENSULFOTHION)

 1,2,3,4,10,10-hexachloro-6,7-epoxy-1,4,4 α ,5,6,7,8,8 α -octahydro-exo-1,4-endo-5,8-dimethanonaphthalene [DIELDRIN]
 1,2,3,4,10,10-hexachloro-5,7-epoxy-1,4,4 α ,5,6,7,8,8 α -octahydro-endo-endo-5,8-dimethanonaphthalene [ENDRIN].

The compounds of formulae I and Ia can be used on their own or together with suitable carriers and/or additives. Suitable carriers and additives may be solid or liquid, and correspond to the substances common in formulation practice, such as, e.g. natural and regenerated substances, solvents, dispersing agents, wetting agents, adhesives, thickeners, binders and/or fertilisers.

For application, the compounds of formulae I and Ia can be processed into the form of dusts, emulsion concentrates, granulates, dispersions, sprays, or solutions, the formulation of these preparations being effected in a manner commonly known in practice. Also to be mentioned are cattle dips and spray races, in which aqueous preparations are used.

The agents according to the invention are produced in a manner known per se by the intimate mixing and/or grinding of active substances of formulae I and Ia with the suitable carriers, optionally with the addition of dispersing agents or solvents which are inert to the active substances. The active substances can be obtained and used in the following preparation forms:

solid preparations: dusts, scattering agents, granulates, coated granulates, impregnated granulates and homogeneous granulates;

liquid preparations:

- water dispersible active substance concentrates: wettable powders, pastes, emulsions;
- solutions.

The solid preparations (dusts, scattering agents) are produced by the mixing of the active substances with solid carriers. Suitable carriers are, e.g. kaolin, talcum, bole, loess, chalk, limestone, ground limestone, attapulgite, dolomite, diatomaceous earth, precipitated silicic acid, alkaline-earth silicates, sodium and potassium aluminium silicates (feldspar and mica), calcium and magnesium sulphates, magnesium oxide, ground

synthetic materials, fertilisers such as ammonium sulphate, ammonium phosphate, ammonium nitrate, urea, ground vegetable products such as bran, bark dust, sawdust, ground nutshells, cellulose powder, residues of plant extractions, active charcoal, etc., alone or in admixture with each other.

Granulates can be very easily prepared by a process in which an active substance of formula I or Ia is dissolved in an organic solvent, the thus obtained solution applied to a granulated mineral, e.g. attapulgite, SiO_2 , granicalcium, bentonite, etc., and the organic solvent then evaporated off.

It is possible also to produce polymer granulates; in this case the active substances of formula I or Ia are mixed with polymerisable compounds (urea/formaldehyde; dicyandiamide/formaldehyde; melamine/formaldehyde, or others); polymerisation is then carefully carried out in a manner which leaves the active substances unaffected, and granulation performed actually during the gel forming process. It is more favourable, however, to impregnate finished porous polymer granules (urea/formaldehyde, polyacrylonitrile, polyester and others), having a specific surface area and a favourable predetermined adsorption/desorption ratio, with the active substances, e.g. in the form of their solutions (in a low-boiling solvent), and to then remove the solvent. Polymer granulates of this kind can be also sprayed in the form of microgranulates, having bulk weights of preferably 300 g/liter to 600 g/liter, with the aid of spray apparatus. Spraying can be carried out over extensive areas of useful plant crops by the use of aeroplanes.

Granulates can also be obtained by the compacting of the carrier material with the active substances and additives, and a subsequent reducing operation.

Moreover, it is possible to add to those mixtures additives stabilising the active substance and/or non-ionic, anion-active and cation-active substances which improve, e.g. the adhesiveness of the active substances on plants and parts of plants (adhesives and agglutinants), and/or ensure a better wettability (wetting agents) as well as dispersibility (dispersing agents).

The following substances are, for example, suitable: olein/lime mixture, cellulose derivatives (methyl cellulose, carboxymethyl cellulose), hydroxyethylene glycol ethers of monoalkyl and dialkyl phenols having 5 to 15 ethylene oxide radicals per molecule and 8 to 9 carbon atoms in the alkyl radical, ligninsulphonic acid, the alkali metal and alkaline-earth metal salts thereof, polyethylene glycol ethers (carbowaxes), fatty alcohol polyglycol ethers having 5 to 20 ethylene oxide radicals per molecule and 8 to 18 carbon atoms in the fatty alcohol moiety, condensation products of ethylene oxide, propylene oxide, polyvinylpyrrolidones, polyvinyl alcohols, condensation products of urea and formaldehyde, as well as latex products.

Water-dispersible concentrates of active substances, i.e. wettable powders, pastes and emulsion concentrates, are agents which can be diluted with water to obtain any desired concentration. They consist of active substance, carrier, optionally additives which stabilise the active substance, surface-active substances, and anti-foam agents and, optionally, solvents.

The wettable powders and pastes are obtained by the mixing and grinding of the active substances with dispersing agents and pulverulent carriers, in suitable devices, until homogeneity is obtained. Suitable carriers are, e.g. those previously mentioned in the case of

solid preparations. It is advantageous in some cases to use mixtures of different carriers. As dispersing agents it is possible to use, e.g.: condensation products of sulphonated naphthalene and sulphonated naphthalene derivatives with formaldehyde, condensation products of naphthalene or of naphthalenesulphonic acids with phenol and formaldehyde, as well as alkali, ammonium and alkaline-earth metal salts of ligninsulphonic acid, also alkylarylsulphonates, alkali metal salts and alkaline-earth metal salts of dibutyl naphthalenesulphonic acid, fatty alcohol sulphates such as salts of sulphated hexadecanols, heptadecanols, octadecanols, and salts of sulphated fatty alcohol glycol ethers, the sodium salt of oleyl methyl tauride, tertiary ethylene glycols, dialkyl dilauryl ammonium chloride, and fatty acid 15 alkali-metal and alkaline-earth metal salts.

Suitable anti-foam agents are, e.g. silicones.

The active substances are so mixed, ground, sieved and strained with the above mentioned additives that the solid constituent in the case of wettable powders has a particle size not exceeding 0.02 to 0.04 mm, and in the case of pastes not exceeding 0.03 mm. For the preparation of emulsion concentrates and pastes, dispersing agents are used such as those mentioned in the preceding paragraphs, organic solvents and water. Suitable solvents are, e.g. alcohols, benzene, xylene, toluene, dimethylsulphoxide, and mineral oil fractions boiling in the range of 120° to 350°C. The solvents must be practically odourless, non-phytotoxic, and inert to the active substances.

Furthermore, the agents according to the invention can be used in the form of solutions. For this purpose, the active substance, or several active substances, of the general formula I and/or Ia is dissolved in suitable organic solvents, solvent mixtures, or water. As organic solvents it is possible to use aliphatic and aromatic hydrocarbons, their chlorinated derivatives, alkylnaphthalenes, mineral oils on their own or in admixture with each other.

The content of active substance in the above described agents is between 0.1 and 95%; it is to be mentioned in this connection that in the case of application of the agents from an aeroplane, or by means of some other suitable application devices, concentrations of up to 99.5% can be used, or even the pure active substance.

The active substances of formulae I and Ia are prepared, e.g. as follows:

Dusts:

The following substances are used for preparation of (a) a 5% dust, and (b) a 2% dust:

- a) 5 parts of active substance
95 parts of talcum.
- b) 2 parts of active substance
1 part of highly dispersed silicic acid
97 parts of talcum.

The active substances are mixed and ground with the carriers.

Granulate:

The following substances are used to produce a 5% granulate:

- 5 parts of active substance.
- 0.25 parts of epichlorhydrin.
- 0.25 parts of cetyl polyglycol ether.
- 3.50 parts of polyethylene glycol.
- 91 parts of kaolin (particle size 0.3 – 0.8 mm).

The active substance is mixed with epichlorhydrin and dissolved with 6 parts of acetone; the polyethylene glycol and cetyl polyglycol ether are then added. The thus obtained solution is sprayed on to kaolin, and the acetone subsequently evaporated in vacuo.

Wettable powder:

The following constituents are used for the preparation of (a) a 40%, (b) and (c) a 25%, and (d) a 10% wettable powder:

10	a)	40	parts of active substance,
		5	parts of sodium lignin sulphonate,
		1	part of sodium dibutyl-naphthalene sulphonate,
		54	parts of silicic acid.
	b)	25	parts of active substance,
		4.5	parts of calcium lignin sulphonate
		1.9	parts of Champagne chalk/hydroxyethyl cellulose mixture (1:1),
		1.5	parts of sodium dibutyl naphthalene sulphonate,
		19.5	parts of silicic acid,
		19.5	parts of Champagne chalk,
		28.1	parts of kaolin.
	c)	25	parts of active substance,
		2.5	parts of isoctylphenoxy-polyoxyethylene-ethanol,
		1.7	parts of Champagne chalk/hydroxyethyl cellulose mixture (1:1),
		8.3	parts of sodium aluminium silicate,
		16.5	parts of kieselguhr,
	d)	46	parts of kaolin.
		10	parts of active substance,
		3	parts of a mixture of the sodium salts of
		5	saturated fatty alcohol sulphates,
		82	parts of naphthalenesulphonic acid/formaldehyde condensate,
30			parts of kaolin.

The active substances are intimately mixed, in suitable mixers, with the additives, the mixture being then ground in the appropriate mills and rollers. Wettable powders are obtained which can be diluted with water to give suspensions of any desired concentration.

Emulsifiable concentrates:

The following substances are used to produce (a) a 10% and (b) a 25% emulsifiable concentrate:

40	a)	10	parts of active substance,
		3.4	parts of epoxidised vegetable oil,
		13.4	parts of a combination emulsifier consisting of fatty alcohol polyglycol ether and alkylarylsulphonate calcium salt,
		40	parts of dimethylformamide,
	b)	43.2	parts of xylene.
		25	parts of active substance,
		2.5	parts of epoxidised vegetable oil,
		10	parts of an alkylarylsulphonate/fatty alcohol-polyglycol ether mixture
		5	parts of dimethylformamide,
50		57.5	parts of xylene.

From these concentrates it is possible to produce, by dilution with water, emulsions of any desired concentration.

Spray:

The following constituents are used to prepare a 5% spray:

60		5	parts of active substance,
		1	part of epichlorhydrin,
		94	parts of ligroin (boiling limits 160°–190°C).

EXAMPLE 1

Production of N,N-dimethyl-N'-(2,6-diethylphenyl)-formamidine.

Production of the compound of the formula

40 ml of dimethylformamide and 40 ml of thionyl chloride are stirred for 2 hours in 200 ml of absolute toluene at 40°C; an addition is then made dropwise at 40°–50°C of 59.8 g of 2,6-diethylaniline diluted with 200 ml of anhydrous toluene. The reaction mixture is heated slowly for 4 hours to the boiling point, and refluxed for a further 5 hours. The reaction mixture is cooled; ice water is added, the whole rendered alkaline with sodium hydroxide solution, and the organic phase separated and dried over sodium sulphate. Distillation yields the product in ca. 85% yield; B.P.: 77°–79°C/0.03 Torr.

The following further compounds are produced in an analogous manner:

N,N-dimethyl-N'-(2,6-dimethylphenyl)-formamidine,	B.P. 132°C/11 Torr
N-methyl-N-butyl-N'-(2,6-dimethylphenyl)-formamidine	B.P. 93°C/0.02 Torr
N-methyl-N'-(2,6-dimethylphenyl)-formamidine,	M.P. 82 – 83°C
N-methyl-N'-(2,6-diisopropylphenyl)-formamidine,	M.P. 62 – 63°C
N-methyl-N'-(2,6-diethylphenyl)-formamidine,	M.P. 165 – 166°C
N-methyl-N'-(2,6-dimethylphenyl)-formamidine,	M.P. 186 – 187°C
N-allyl-N'-(2,6-dimethylphenyl)-formamidine,	M.P. 45°C
N-propargyl-N'-(2,6-dimethylphenyl)-formamidine,	oil
N,N-dimethyl-N'-(2,4,6-trimethylphenyl)-formamidine,	B.P. 72–73°C/0.09 Torr
N'-methyl-N'-(2,4,6-trimethylphenyl)-formamidine,	M.P. 123 – 124°C
N,N-dimethyl-N'-(2-ethyl-6-sec.butyl-phenyl)-formamidine,	
N-methyl-N-n-butyl-N'-(2-ethyl-6-n-butyl-phenyl)-formamidine,	
N,N-dimethyl-N'-(2-ethyl-6-isopropylphenyl)-formamidine,	
N-methyl-N-n-butyl-N'-(2-ethyl-6-iso-propylphenyl)-formamidine,	
N,N-dimethyl-N'-(2-methyl-6-tert.butyl-phenyl)-formamidine,	
N-methyl-N-n-butyl-N'-(2,6-diethylphenyl)-formamidine,	
N,N-dimethyl-N'-(2-methyl-6-ethylphenyl)-formamidine,	
N,N-dimethyl-N'-(2,6-diisopropylphenyl)-formamidine,	
N-methyl-N-n-butyl-N'-(2-methyl-6-iso-propylphenyl)-formamidine.	

EXAMPLE 2

Action against ticks

A. *Rhipicephalus bursa*

In each case, 5 adults or 50 tick larvae were placed

into a small glass test tube, and the test tubes them immersed for 1 to 2 minutes in 2 ml of an aqueous emulsion from a dilution series of 100, 10, 1 and 0.1 ppm of test substance. The tubes were then sealed with a standardised cotton plug, and inverted so that the active substance emulsion could be absorbed by the cotton wool.

An evaluation in the case of the adults was made after 2 weeks, and in the case of the larvae after 2 days. There were two repeats for each test.

The compounds according to Example 1 were effective, in the above test, against adults and larvae of *Rhipicephalus bursa*.

15 B. *Boophilus microplus* (larvae)

With a dilution series analogous to that in Test A, tests were carried out in each case with 20 OP-sensitive larvae.

20 The compounds according to Example 1 were effective in the above test against sensitive larvae of *Boophilus microplus*.

We claim:

- 55 1. N,N-dimethyl-N'-(2-methyl-6-ethyl-phenyl)-formamidine.
 2. N-methyl-N-n-butyl-N'-(2,6-diethyl-phenyl)-formamidine.
